(57) **ABSTRACT**

A cornhole game board providing an interchangeable faceplate display is provided. The game board includes a framework having a plurality of peripheral elements defining an opening into which a faceplate may be inserted. Each peripheral element may define a portion of a coplanar slot extending along the game board framework, wherein one of a plurality of faceplates may be slidably received or removed in the resulting coplanar slot. Thereby the game board provides a variety of interchangeable playing surfaces of cornhole.

INTERCHANGEABLE GAMEBOARDS

BACKGROUND OF THE INVENTION

The present invention relates to interchangeable game boards and, more particularly, a cornhole game board adapted to slidably receive interchangeable faceplates.

The game of cornhole, also known as dummy boards, bean bag toss, and other names is an American lawn game in which players take turns throwing bags of corn at a raised platform with a hole in the far end, scoring points for getting a bag in the hole or to land and stay on the platform. Current cornhole game boards have a static and permanent platform or "playing surface," and thus they lack the ability to change designs on the playing surface without completely deconstructing the actual board. Thus, if a playing surface becomes worn, warped, or weathered, a user cannot replace the playing surface without purchasing an entirely new game board. Similarly, if a user follows multiple teams or otherwise would like multiple designs on their playing surface, they would need to have multiple game boards, which would consume both money and storage space.

As can be seen, there is a need for a game board frame adapted to slidably receive interchangeable faceplates for providing a variety of playing surfaces, effectively utilizing only one game board frame to do so.

SUMMARY OF THE INVENTION

In one aspect of the present invention, a cornhole game board includes two spaced apart longitudinal elements; a base element interconnecting the two longitudinal elements so as to define an opening, wherein the base element is connected near a respective first end of each of the two longitudinal elements; a longitudinal slot provided by each of the two longitudinal elements so that the longitudinal slots are coplanar; a plurality of faceplates, each dimensioned and adapted to slide into the longitudinal slots so as to be substantial visible through the opening; and a cornhole provided by each faceplate.

In another aspect of the present invention, the cornhole game board, includes two spaced apart longitudinal elements; a base element interconnecting the two longitudinal elements so as to define an opening, wherein the base element is connected near a respective first end of each of the two longitudinal elements; a top element interconnecting the two longitudinal elements near a respective second end of each of the two longitudinal elements; a longitudinal slot provided by each of the two longitudinal elements; a base slot provided by the base element so that the base slot is coplanar with the longitudinal slots; a leg provided by each of longitudinal elements for propping up a respective second end of each of the two longitudinal elements; a plurality of faceplates, each dimensioned and adapted to slide into the longitudinal slots so as to be substantial visible through the opening; a dado along a portion of a periphery of each faceplate; a cornhole provided by each faceplate; and at least one corn bag dimensioned to be received through the cornhole.

These and other features, aspects and advantages of the present invention will become better understood with reference to the following drawings, description and claims.

BRIEF DESCRIPTION OF THE DRAWINGS

FIG. 1 is a perspective view of an exemplary embodiment of the present invention, shown in use;

2

FIG. 2 is a perspective view of an exemplary embodiment of the present invention, illustrating a faceplate being removed;

FIG. 3 is an exploded view of an exemplary embodiment of the present invention;

FIG. 4 is a front elevation view of an exemplary embodiment of the present invention;

FIG. 5 is a top plan view of an exemplary embodiment of the present invention;

FIG. 6 is a bottom plan view of an exemplary embodiment of the present invention;

FIG. 7 is a section view of an exemplary embodiment of the present invention, taken along 7-7 in FIG. 1;

FIG. 8 is an enlarged section view of an exemplary embodiment of the present invention;

FIG. 9 is an enlarged section view of an exemplary embodiment of the present invention; and

FIG. 10 is a section view of an exemplary embodiment of the present invention, taken along 10-10 in FIG. 7.

DETAILED DESCRIPTION OF THE INVENTION

The following detailed description is of the best currently contemplated modes of carrying out exemplary embodiments of the invention. The description is not to be taken in a limiting sense, but is made merely for the purpose of illustrating the general principles of the invention, since the scope of the invention is best defined by the appended claims.

Broadly, an embodiment of the present invention may include a cornhole game board providing an interchangeable faceplate display. The game board includes a framework having a plurality of peripheral elements defining an opening into which a faceplate may be inserted. Each peripheral element may define a portion of a coplanar slot extending along the game board framework, wherein one of a plurality of faceplates may be slidably received or removed in the resulting coplanar slot. Thereby the game board provides a variety of interchangeable playing surfaces of cornhole.

Referring now to FIGS. 1 through 10, the present invention may include a cornhole game board 50 providing interchangeable faceplate 10 capabilities. The game board 50 may provide a framework 48 having a plurality of peripheral elements defining an opening 46 into which one of a plurality of faceplates 10 may be inserted. The plurality of peripheral elements may include a pair of opposing longitudinal elements 24, 20 and a base element 24 interconnecting opposing ends of the longitudinal elements 24, 20. The base element 24 and the longitudinal elements 24, 20 may be contiguous to each other so as to define a substantially coplanar peripheral inner edge 19 defining the opening 46. The plurality of peripheral elements may be made of cardboard, plastic, wood, various fibrous materials or the like.

In certain embodiments, the plurality of peripheral elements may include a top element 28 interconnect to the opposing longitudinal elements 24, 20 on an end opposing the base element 24. The top element 28 may be adapted to provide lateral support for the opposing longitudinal elements 24, 20. The interconnections of the plurality of peripheral elements may be done by way of fasteners 38. The plurality of peripheral elements may form a parallelogram shape, as illustrated in the Figures, however any shape that functions in accordance with the disclosure herein is also sufficient.

Each peripheral element may define a portion of a coplanar slot **18, 22, 26** extending approximately the entire length of a periphery of the opening **46**, as illustrated in FIGS. 9 and **10**. The portions of the coplanar slot **18, 22, 26** in their totality provide a coplanar slot or groove for slidably receiving at least one faceplate **10**. In certain embodiments, the coplanar slot may be formed by portions **18, 22** of the opposing longitudinal elements **24, 20**. The resulting coplanar slot may be adapted so that each faceplate **10** can be slidably received so as to be visible through the opening **46**. The top element **28** may be disposed downward (relative to the supporting surface **44**) from the peripheral inner edge **19** so that the faceplate **10** slides over the top element **28**.

The faceplate **10** may provide a peripheral dado **14** to facilitate the sliding reception within the coplanar slot. The faceplate **10** may have a design, messages, imagery or the like that a user **42** may wish to display, for example of a logo of the user's favorite sports team. The faceplate **10** may form at least one cornhole **12**. In certain embodiments, the at least one cornhole **12** may be adapted to receive at least one corn bag **40** thrown by the user **42** when playing the cornhole game, as illustrated in FIG. 1.

The framework **48** may include a leg **30** connected to the each of the pair of the opposing longitudinal elements **16, 20** so as to prop up one end the framework **48** so that the faceplate **10** is oriented at an acute angle relative to a ground surface **44** supporting the framework **18**, as illustrated in FIG. 7. Each leg **30** may be connected to each longitudinal/peripheral element **16, 20** by way of fasteners **32, 34, 36**, so as to be pivotally connected thereto, as illustrated in FIG. 3. The leg(s) **30** may be alternatively attached to the top element **28**.

A method of making the present invention may include the following. An individual may provide equipment comprising two 48" 2x4's, two 24" 2x4's, and a 23" x 46" piece of plywood. It may also be necessary to have a dado blade to make the cuts forming the coplanar slot or portions thereof. The initial step may include cutting the two 48" pieces of 2x4 and two 24" pieces of 2x4. Then the individual may then run a $\frac{5}{8}$ " dado cut, $\frac{1}{4}$ " from the top of the 2x4, along the inside of every piece of wood at a depth of $\frac{3}{4}$ ". The individual may then screw the 48" pieces to one of the 24" pieces to make a "U" shape with the dado cuts lining up. A 21" piece of 2x4 may be installed at the open end of the "U" so create the framework **48**. To make a faceplate **10**, the individual may then take a $1\frac{1}{2}$ " thick piece of plywood and cut it to measure 23" x 46". You must run a $\frac{5}{8}$ " dado at $\frac{1}{4}$ " deep along the inside perimeter of the plywood. You will be able to insert the faceplate **10** into the framework **48** by sliding it in the top of the "U".

In certain embodiments, the individual make manufacture the interchangeable faceplate display **10** by the following:

Cut (4) 2x4's into a 4' piece;

Cut (4) 2x4's into a 2' piece;

Run a $\frac{5}{8}$;

Cut a 45 degree angle on opposite ends of the pieces of wood;

Screw 2 of the 4' pieces to one of the 2' pieces, with the dado cut up;

Screw a 21;

Cut a 21;

Run a $\frac{5}{8}$;

Measure 9;

Slide in plywood to the frame;

Drill a $\frac{1}{2}$;

Insert a 4;

Cut a (2)10.5;

Drill a $\frac{1}{4}$;
Slide 10.5;
Slide the last 2' piece onto the top of the set;
Drill a $\frac{1}{4}$; and
Run a 6

A method of using the present invention may include the following. The cornhole game board **50** disclosed above may be provide. A user may slide a first faceplate **10** into the coplanar slots **18, 22** provided by the framework **48** so as to display the first faceplate **10** through the opening **46**. Then, when the user wants a different display, the user may slidably remove the first faceplate **10** so as to exchange it with a second faceplate **10**, whereby the second faceplate **10** is slidably received in the coplanar slots **20**. Then the user may play the game cornhole.

It should be understood, of course, that the foregoing relates to exemplary embodiments of the invention and that modifications may be made without departing from the spirit and scope of the invention as set forth in the following claims.

What is claimed is:

1. A cornhole gameboard, comprising:
two spaced apart longitudinal elements, said two spaced apart longitudinal elements each having a vertex at a first end of both longitudinal elements;

a base element comprising two ends each having a vertex that are obliquely opposed to both longitudinal element's first ends, said obliquely opposed vertexes interconnecting the two longitudinal elements so as to define an opening, wherein the two base element ends are each independently connected near the respective first ends of each of the two longitudinal elements as to form two obliquely opposed vertex connections;
a longitudinal slot provided by each of the two longitudinal elements so that the longitudinal slots are coplanar;

a plurality of faceplates, each of said faceplates having at least one corn hole that passes from a top surface to a bottom surface and each of said faceplates dimensioned and adapted with a dado along a first and a second side to slide into the longitudinal slots so as to be substantially visible through the opening, wherein said dado is configured to facilitate the sliding reception within the coplanar slots of said plurality of faceplates having at least one cornhole; and

a top element, the element opposing the base element, the top element comprising two ends configured to provide lateral support for the longitudinal elements, the top element disposed downward such that that the plurality of faceplates is configured to slide over the top element; at least one corn bag, wherein said at least one cornhole provided by each plurality of faceplates are configured to allow passage of said at least one corn bag from said top surface to a ground surface;

a base slot provided by the base element so that the base slot is coplanar with the longitudinal slots; the two spaced apart longitudinal elements each having a 45-degree vertex at the first end of both longitudinal elements;

the two ends of the base end each having a 45-degree vertex;

a leg connected to each of the longitudinal elements configured for propping up a respective second end of each of the two longitudinal elements off of the ground surface;

the legs connected to each of the longitudinal elements, when parallel with the ground surface, configured to be

positioned in a recess created by the top element, the longitudinal elements, and the faceplate, the top element when in this position configured to be in contact with the ground surface, the legs when in this position configured to not be in contact with the ground surface.

2. The gameboard of claim 1, further comprising: legs connected to the top element configured for propping up the gameboard.

3. The gameboard of claim 1, the top element having a top surface and bottom surface, the bottom surface of the top element extending below the base element and longitudinal elements when the bottom surface is parallel with the ground surface, the base component extending above the top surface of the top element when the top element is parallel with the ground surface.

4. A cornhole gameboard, comprising:

two spaced apart longitudinal elements, said two spaced apart longitudinal elements each having a 45 degree vertex at a first end of both longitudinal elements;

a base element comprising two ends each having a 45 degree vertex that are obliquely opposed to both longitudinal element's first ends, said obliquely opposed vertexes interconnecting the two longitudinal elements so as to define an opening, wherein the base elements two ends are each independently connected near the respective first ends of each of the two longitudinal elements as to form two obliquely opposed vertex connections;

a longitudinal slot provided by each of the two longitudinal elements so that the longitudinal slots are coplanar;

a plurality of faceplates, each of said faceplates having at least one cornhole that passes from a top surface to a bottom surface and each of said faceplates dimensioned and adapted with a dado along a first and a second side to slide into the longitudinal slots so as to be substantially visible through the opening, wherein said dado is configured to facilitate the sliding reception within the coplanar slots of said plurality of faceplates having at least one cornhole; and

a top element comprising two ends configured to provide lateral support for the longitudinal elements, the top element disposed downward such that that the plurality of faceplates are configured to slide over the top element, the top element having a top surface and bottom surface, the bottom surface of the top element extending below the longitudinal elements and the base component when bottom surface is parallel with the ground surface, the base element extending above the top of the top element when the top element is parallel with the ground surface;

at least one corn bag, wherein said at least one cornhole provided by each plurality of faceplates are configured to allow passage of said at least one corn bag from said top surface to a ground surface;

a base slot provided by the base element so that the base slot is coplanar with the longitudinal slots;

the two spaced apart longitudinal elements each having a 45-degree vertex at the first end of both longitudinal elements;

the two ends of the base end each having a 45-degree vertex;

a leg connected to each of the longitudinal elements configured for propping up a respective second end of each of the two longitudinal elements off of the ground surface;

the legs connected to each of the longitudinal elements, when parallel with the ground surface, configured to be positioned in a recess created by the top element, the longitudinal elements, and the faceplate, the top element when in this position configured to be in contact with the ground surface, the legs when in this position configured to not be in contact with the ground surface.

5. The gameboard of claim 4, further comprising a base slot provided by the base element so that the base slot is coplanar with the longitudinal slots.

6. The gameboard of claim 5, further comprising: at least one corn bag, wherein said at least one cornhole provided by each plurality of faceplates are configured to allow passage of said at least one corn bag from said top surface to a ground surface.

7. The gameboard of claim 6, further comprising: a leg provided by each of said two longitudinal elements configured for propping up a respective second end of each of the two longitudinal elements off of the ground surface.

8. The gameboard of claim 7, further comprising: legs connected to the top element configured for propping up the gameboard.

9. A method of changing a faceplate for a cornhole gameboard, the method comprising:

sliding a first faceplate into two spaced apart longitudinal slots, said two spaced apart longitudinal elements each having a vertex at a first end of both longitudinal elements, wherein the first faceplate visible through an opening in the framework, the framework comprising a base element comprising two ends each having a vertex that are obliquely opposed to both longitudinal element's first ends, said obliquely opposed vertexes interconnecting the two longitudinal elements so as to define an opening, wherein the base elements two ends are each independently connected near the respective first ends of each of the two longitudinal elements as to form two obliquely opposed vertexes connections, a longitudinal slot provided by each of the two longitudinal elements so that the longitudinal slots are coplanar, a top element comprising two ends configured to provide lateral support for the longitudinal elements, the top element disposed downward such that that the plurality of faceplates slides over the top element, the bottom surface of the top element extending below the base component when bottom surface is parallel with the ground surface, the base element extending above the top of the top element when the top element is parallel with the ground surface;

at least one corn bag, wherein said at least one cornhole provided by each plurality of faceplates are configured to allow passage of said at least one corn bag from said top surface to a ground surface;

a base slot provided by the base element so that the base slot is coplanar with the longitudinal slots;

the two spaced apart longitudinal elements each having a 45-degree vertex at the first end of both longitudinal elements;

the two ends of the base end each having a 45-degree vertex;

a leg connected to each of the longitudinal elements configured for propping up a respective second end of each of the two longitudinal elements off of the ground surface;

the legs connected to each of the longitudinal elements, when parallel with the ground surface, configured to be positioned in a recess created by the top element, the longitudinal elements, and the faceplate, the top ele-

ment when in this position configured to be in contact with the ground surface, the legs when in this position configured to not be in contact with the ground surface.

10. The method of claim **9**, further comprising: sliding the first faceplate out from the two spaced apart longitudinal slots. 5

11. The method of claim **10**, further comprising: sliding a second faceplate into the two spaced apart longitudinal slots.

12. The method of claim **11**, the framework further comprising at least one corn bag, wherein said at least one ¹⁰ cornhole provided by each plurality of faceplates are configured to allow passage of said at least one corn bag from said top surface to a ground surface, a base slot provided by the base element so that the base slot is coplanar with the longitudinal slots, two spaced apart longitudinal elements ¹⁵ each having a 45-degree vertex at the first end of both longitudinal elements, the two ends of the base end each having a 45-degree vertex.
